UNITED STATES PATENT OFFICE.

JEROME WARD, OF WAUKEGAN, ILLINOIS, ASSIGNOR TO BLATCHFORD CALF MEAL CO., OF WAUKEGAN, ILLINOIS.

BEATER FOR GRINDERS.

1,401,017.

Specification of Letters Patent. Patented Dec. 20, 1921.

Application filed August 2, 1920. Serial No. 400,689.

To all whom it may concern:

Be it known that I, JEROME WARD, a citizen of the United States, residing at Waukegan, in the county of Lake and State of Illinois, have invented certain new and useful Improvements in Beaters for Grinders, of which the following is a specification.

This invention relates more particularly to the beaters or grinding members of centrifugal grinding or pulverizing machines, such as are used for grinding or the like. When the ordinary flat beaters are used with these machines, the material which is being ground appears to gather or accumulate at the ends of the beaters where the main grinding occurs and consequently the ends become more or less rapidly worn off.

The objects of this invention are to provide an improved beater for grinding machines; to provide a beater which will direct the material so that it will be properly distributed in the casing of the mill; to provide a beater which will increase the grinding or pulverizing action; and in general, to provide such an improved device as will be described more fully hereinafter.

In the accompanying drawings showing a preferred form of my device:

Figure 1 is a diagrammatical sectional view of a grinding mill showing the beater in position;

Fig. 2 is an enlarged front view of the beater;

Fig. 3 is a sectional view taken on the line 3—3 of Fig. 2; and,

Fig. 4 is an end view.

As shown in these drawings, 5 represents the casing of a pulverizer or grinding machine having an intake 6. The beaters 7 are carried on arms 8 in the usual manner. These beaters may be made of any suitable material but are preferably cast in the shape shown and are secured to the arms by means of rivets 9. These beaters are made thicker at their outer edges 10 than at their inner edges 11 as will be readily seen from Fig. 4. They are also somewhat thicker at the ends 12 than at the middle so that they have somewhat concave faces as will be seen from Fig. 3. The grinding faces are preferably roughened or corrugated as shown at 13 in

order to increase the grinding action. They are also provided with one or more diagonally arranged ribs 14, which tend to force or direct the material from the inlet 6, toward the opposite side of the casing.

From this description it will be seen that not only are the usual portions of the beaters considerably thickened, but such thickening and conformation of the plates tends to distribute the material more evenly across the mill so that all of the grinding parts are worn more evenly. Furthermore the concave faces of the beaters tend to prevent the material from collecting at the ends or in the corners of the casing. I have found that in actual practice these beaters will last longer than the ordinary flat beaters and will do more efficient work. It will be noted that the form and size of the beaters may be modified for different mills, and therefore I do not wish to be limited to the exact construction herein shown and described except as specified in the following claims.

I claim—

1. A beater for grinders, comprising a substantially rectangular plate which is thicker on the outer edge than at the inner edge and thicker at the ends than at the middle, thereby forming a substantially concave grinding face longitudinally of the beater.

2. A beater of the character set forth having a head portion which is thicker at the outer edge than at the inner edge and thicker at the ends than at the middle and is provided with one or more diagonally arranged ribs on the face thereof.

3. An improved beater comprising a plate which is tapered from the outer edge toward the inner edge and tapered from the ends toward the middle and provided with a roughened grinding face substantially as described.

4. A beater for grinders, comprising a substantially rectangular cast plate having its grinding faces tapering from the outer edge toward the inner edge and beveled from the ends toward the middle and provided with one or more diagonally arranged deflecting ribs.

JEROME WARD
